RESISTANCE WELDER

Daniel Marie Duinker and Roelf Oostra, Eindhoven, Netherlands, assignors, by mesne assignments, to Hartford National Bank and Trust Company, Hartford, Conn., as trustee

Application November 24, 1937, Serial No. 176,344
In Germany December 14, 1936

2 Claims. (Cl. 250—27)

Our invention relates to resistance welders which are operated from alternating current mains, and more particularly, to automatically-timed welders.

With such welders it is necessary that the welding current—which frequently amounts to several thousand amperes—flows through the material being welded for short and preferably variable time periods and at regular time intervals. As mechanically-operated switches are not entirely satisfactory for this purpose, the timing is generally effected by means of a grid-controlled, gas-filled tube having either an incandescent or mercury cathode, i. e., a relay tube.

It has been proposed to control spot-seam welders by means of an alternating potential which has a variable frequency and is produced by a separate device. However, we have found that in practice such control devices have the disadvantage that variation of the duration of the welding-current impulses also introduces a variation in the duration of the currentless time intervals, i. e., the period between the welds.

The object of our invention is to overcome the above difficulties, and to provide a welder which may be used for either spot or spot-seam welding and in which the time of the duration of the current impulses and the currentless intervals can be varied independently of each other.

In accordance with the invention we control the duration of the current impulses and the duration of the currentless periods by similar arrangements, each of which comprises a retarding chain consisting of at least one condenser and a resistance which controls the conductivity of the discharge path of a gaseous-filled discharge tube, preferably a grid-controlled tube. We so arrange these chain arrangements that the duration of the current impulses and the duration of the currentless periods can be adjusted independently of each other.

The arrangement is preferably such that the condensers of the retarding chains when in their charged condition block the auxiliary discharge path or paths, and are charged either indirectly or directly by the welding current or by a current corresponding thereto.

We are aware that it has been proposed to control the duration of welding-current impulses by inserting a condenser, which has been step-wise charged through a rectifier, in the grid circuit of a gaseous-filled discharge tube, whereby the grid will receive after a controllable time such a negative voltage that the discharge path of the tube becomes non-conductive. However, in

an arrangement according to the invention, the time of the welding-current impulse is determined by a condenser which is connected between the grid and cathode of an auxiliary discharge path and is charged by a second condenser through a preferably variable resistance, whereby the negative bias of a control grid of the auxiliary discharge tube associated with the first condenser gradually increases to such an extent that after a certain time the discharge path becomes non-conductive; the second condenser being charged through a rectifier as soon as a welding current flows.

In accordance with one embodiment of the invention, we use an auxiliary discharge tube having, for instance, two grids, and apply to one of these grids a negative voltage which blocks the discharge path, and so arrange the circuits that the entire apparatus becomes inoperative upon applying this negative voltage.

In order that the invention may be clearly understood and readily carried into effect, we shall describe the same in more detail with reference to the accompanying drawing in which the single figure is a circuit diagram of a welder according to the invention. The welder illustrated may be used for either spot or for spot-seam welding, and is provided with a two-pole double-throw switch 27 for this purpose. When switch 27 is in position A as shown, the apparatus is adapted for spot welding, and when it is in its second position B the apparatus is adapted for spot-seam welding.

In the figure, reference numeral 1 indicates an object to be welded which is connected across a secondary winding 30 of a step-down transformer 2 having a primary winding 31. Winding 31 has one end connected to one terminal of an alternating current source 3, which may be the ordinary supply mains, and its other end connected to the other terminal of source 3 through a secondary winding 32 of a coupling transformer 4 having a primary winding 33.

Winding 33 is connected in the plate circuit of a grid-controlled discharge tube 5 having a grid circuit including a biasing battery 35, a winding 36, and a resistance 34. When tube 5 is non-conductive, the effective impedance of winding 32 is very high, and only a small current can flow through winding 31, and as a result there will be no effective flow of welding current in winding 30. However, when tube 5 is conductive the effective impedance of winding 32 becomes very small or disappears entirely, and the current through

winding 31 and thus the welding current attains a high value.

In order to make tube 5 conductive for a definite time, we use a control device comprising 5 a gaseous-filled discharge tube 6, i. e., a relay tube, having two grids 7 and 8, a plate 40, and a cathode 10 which is shown as being indirectly heated but which may be directly heated.

Tube 6 has a plate circuit including a secondary winding 39 of a transformer 11 whose primary winding 38 is connected across source 3, a winding 37 forming part of a transformer 15 which also comprises the winding 36. The grid of tube 5 is normally sufficiently negatively biased by battery 35 so that the current will not flow through winding 33. However, when an alternating current flows in the plate circuit of tube 6, an alternating voltage will be induced in the grid circuit of tube 5 to thereby make this tube 20 conductive.

To control the moment at which the welding current will start to flow, grid 7 is connected through a source of potential 9, shown as a transformer, conductor 41, resistance 13, biasing battery 12, and conductor 42, to cathode 10, to thereby form a grid circuit. Source 9 has a frequency corresponding to that of source 3 and preferably has a sharp curve shape to ensure that the starting of the discharge device takes 30 place at exactly the same moment of every cycle and will not vary with voltage variations of source 3 or temperature changes and accordingly varying gas pressure of the discharge devices. This potential may be obtained from source 3 35 through a phase-shifter 57, for instance a reactance coil with a movable core, which serves to vary the phase of the voltage of source 9. Battery 12 negatively biases grid 7 to such an extent that tube 6 is blocked and source 9 does not affect 40 the plate current of this tube.

When it is desired to weld, a two-pole double-throw switch 14 is used. Switch 14 has two arms 43 and 44, and can be placed in two positions, C and D. By placing the switch in position D arm 45 44 completes a shunt circuit across resistance 13 and a portion of battery 12, whereby the grid bias of tube 6 is reduced to such a degree that this tube becomes conductive upon the occurrence of a voltage peak of source 9. The moment at 50 which this peak occurs is determined by the relation between the phases of the voltages of source 9 and source 3, and by varying this phase relation the moment of each half cycle in which current will flow through the plate current of tube 6 can 55 be controlled. Thus, with switch 14 in position D, a series of current impulses takes place in the plate circuit of tube 6, and this in turn induces in the grid circuit of tube 5 a voltage which makes this tube intermittently conductive. As a result 60 a welding current will flow whose intensity can be controlled by varying the phase of source 9.

To interrupt this current after a certain time period of regulable length, we provide means to control tube 6 by means of grid 8. For this purpose, we connect between grid 8 and cathode 10, a grid circuit comprising a condenser 18 and a rectifier 17 connected in series across a winding 16 provided on transformer 15. The first impulse of current at the beginning of the welding 65 cycle will produce a current in winding 16, which current after being rectified will charge condenser 18. During the welding condenser 18 charges a variable condenser 19 through a variable resistance 20. Condenser 19 has one end 70 connected to cathode 10 and its other end con-

nected through a limiting resistance 21 to grid 8 in such a manner that as the voltage of this condenser becomes higher, grid 8 becomes more negatively biased. By varying the capacity of condenser 19 and the resistance of resistance 20, 5 it is possible to determine the time required for condenser 19 to be charged to a voltage which will sufficiently bias grid 8 to block tube 6 and thus the duration of flow of welding current.

When switch 14 is placed in position C, condensers 18 and 19 are discharged through a circuit including conductor 42, arm 43, and a resistance 45; the discharging of condenser 19 being facilitated by a rectifier 28 connected across resistance 20. As arm 44 is open, grid 7 is negatively biased and tube 6 remains blocked.

If the device is now to be used for spot-seam welding, switch 27 is placed in position B, whereby a regular series of current impulses is produced, and the duration of the currentless time intervals can be adjusted independently of the duration of these impulses. Such independent control is very advantageous particularly when welding objects of different shape from the same material. This circuit arrangement of the retarding 25 chain for determining the duration of currentless time intervals operates in a similar manner to the other retarding chain.

For the above purpose, a winding 22 provided on transformer 15 has one end connected through 30 a conductor 46 to one terminal of a variable condenser 24 whose other terminal is connected through conductors 47 and 48, and a rectifier 23 to the other end of the winding 22. Thus condenser 24 is charged to its full extent during the 35 whole welding period.

Condenser 24 has one terminal connected through a limiting resistance 49 to a grid 51 of a discharge tube 26, preferably having a screen-grid 52, and has its other terminal connected 40 through conductor 47 to the cathode of this tube to thereby impress such a negative voltage on grid 51 as to make tube 26 non-conductive. Condenser 24 is shunted by a variable resistance 25 whereby tube 26 will become conductive again 45 after a predetermined time and short-circuit condensers 18 and 19.

For this purpose, condenser 18 is connected in the plate circuit of tube 26, which circuit may be traced from the plate of this tube through a 50 conductor 53, a winding 50 of transformer 29, a conductor 54, arm 55 of switch 27, conductor 56, condenser 18, and conductor 48 to the cathode of tube 26. As condenser 19 in series with the rectifier 28 is shunted across condenser 18, it 55 will discharge in a similar manner.

To insure complete discharge of condenser 18 the primary winding of transformer 29 is connected to the source 3.

After condensers 18 and 19 have been discharged in the above manner through tube 26, tube 6 may again be ignited, whereby a new cycle begins.

While we have described our invention with reference to specific examples and applications, 65 we do not wish to be limited thereto but desire the appended claims to be construed as broadly as permissible in view of the prior art.

What we claim is:

1. In a control device for controlling the flow 70 of current in a load circuit, a gaseous discharge tube for controlling the flow of load current and having a control grid, a timing condenser connected to said control grid to apply a blocking voltage thereto, and means for charging said con- 75

5 denser comprising a resistance, a second condenser connected across said first condenser with the interposition of said resistance, and means to charge said second condenser to always the same polarity with direct current when current flows in the load circuit.

10 2. In a control device in which a load current is controlled by a gaseous discharge tube having a control electrode, means for applying a blocking voltage to said electrode comprising a

condenser, a charging circuit for said condenser including a resistance and a second condenser, and means for charging said second condenser to always the same polarity, said means comprising a charging circuit including a rectifier 5 and a supply source, said supply source being effective upon the flow of the load current.
